HARVESTER.

No. 20,334.

Patented May 25, 1858.

UNITED STATES PATENT OFFICE.

I. H. CONKLIN, OF ROCKFORD, ILLINOIS.

IMPROVEMENT IN HARVESTERS.

Specification forming part of Letters Patent No. 20,334, dated May 25, 1858.

To all whom it may concern:

Be it known that I, I. H. CONKLIN, of Rockford, in the county of Winnebago, in the State of Illinois, have invented certain new and useful Improvements in Harvesting-Machines; and I do hereby declare that the following is a full and exact description thereof, reference being had to the accompanying drawings, and to the letters of reference marked thereon.

The nature of my invention consists in certain improvements in the cutting apparatus and attachments thereof, as hereinafter fully described.

To enable those skilled in the art to make and use my invention, I will proceed to describe its construction and operation, referring by letters to the accompanying drawings, forming part of this specification, in which—

Figure 1 represents a perspective view of a harvester, with the omission of the driving apparatus and grain-platform, embracing my improvements; Fig. 2, a top view of the cutting apparatus and vibrating divider; Fig. 3, a partial back edge view of the cutting arrangement and vibrating divider; Fig. 4, skeleton views, showing the peculiar motions or operation of the vibrating divider; and Fig. 5, a top view of the cutting apparatus with the holder-plate D removed.

Similar letters denote the same parts in different views.

A represents a segmental finger-bar, upon which the fingers are arranged, and which is supported by a horizontal shaft, a, having its bearings in the forward ends of the sides of the frame B. Said frame is constructed of three pieces, as seen at B B B, Fig. 1, which are firmly secured together by four bolts, r r r r.

e e, &c., are the fingers, projecting from the front edge of the bar A; E E, &c., the cutters, and e, the cutter-bar, which is held down upon the upper side of the finger-bar A by means of a plate, D, secured by bolts b b. The cutter-bar e, although held down upon the finger-bar, is allowed to move upon said finger-bar in the arc of a circle concentric with the circles in which the fingers and cutters lie, and to such extent in either direction as is equal to the distance between the fingers. The cutter-bar is rendered capable of such motion in such direction only by means of its peculiar construction and that of the holder-plate D, as will be hereinafter fully described.

G is the vibrating divider, which is constructed of the form substantially as shown in the drawings. Said divider has a long narrow shank, n, through which, at its junction with the butt of the divider, is made a hole to accommodate the pin p, by which pin said divider is pivoted in the front end of the shield C, the shank n passing into the hollow side frame, B, and through a slot cut in the end of the cutter-bar e, by which cutter-bar the divider is vibrated upon its pivot p in a horizontal plane.

S is a vibrating arm operated by any desirable driving mechanism, which works at its butt on a pivot, r, in the frame B, and the forward end of which passes through a slot in the end of the cutter-bar opposite, and similar to that through which the shank n of the divider G passes.

c² c² are two slots in the cutter-bar e, of sufficient width to accommodate the two pins a² a², which project upward from the finger-bar A to a height equal to the thickness of the cutter-bar e. Said slots are formed in a curve concentric with that passing through the cutters and of sufficient length to allow the cutter-bar e to vibrate the desired length of stroke, the pins a² a² being of such diameter as to fill the width of the slots, prevent any lateral play to the bar e, while the plate D, when properly secured by its screws b b, prevents any up and down play to said bar.

It will be observed that at each end of the cutter-bar e its rear edge is bent up and somewhat around, so as to lie nearly in the surface of a cylinder, this bent-up portion being tapered down toward that part where the cutters commence. This peculiar formation of said bar e, which is readily comprehended by reference to the drawings, enables me to accomplish two very desirable results, viz.: a direct attachment of the vibrating driving-lever or arm s to the vibrating cutter-bar e without the use of any joints or other mechanism, the said arm s producing legitimately in the said cutter-bar e the desired motion, while the said bar e and arm s move in curves eccentric to each other; also the direct attachment of the cutter-bar e to the shank n of the vibrating divider, whereby said divider is actuated in the desired manner by said cutter-bar without any complication of mechanism, and while the circumferences of the circle, in which said di-

vider and bar move intersect each other. It will be seen that these desirable results are dependent upon the shape of the ends of the cutter-bar, as described, being bent up, as shown, and slotted to receive the ends of the lever *s* and shank *n*, which slide longitudinally through said slots while they vibrate in the arcs of circles.

It will be observed that the ends of the plate *D*, near the front edge, are "upset" or shelled out to allow a portion of the turned-up part of the bar *e* to pass under. This is only necessary on account of the advantage to the bar *e* of an extension of its turned-up edge giving rigidity to its ends, which have some strain to bear consequent to the variable directions of its motion and that of the driving-lever *s*.

The shaft *a*, it will be seen, is semicircular in its cross-section, with the exception of its extreme ends, which must be perfectly cylindrical to form journals fitting into suitable bearings in the sides of the frame *B*, and in which said shaft is oscillated at pleasure by means of a lever, *m*, fitted to the projecting and squared end *n'* of said shaft. The form of the shaft *a* is not material, provided its ends form journals to fit in bearings in the frame *B*, as described, and the remaining portion is so constructed as to render the attachment of the segmental finger-bar *A* practical and its support certain, the object of attaching said finger-bar to said shaft, as described, being to enable the operator to vary the plane in which the cutting apparatus lies at pleasure without effecting any other portion of the machine, which is particularly desirable in passing over ground with very short risings and fallings.

F F are the reel posts or bearers, which are braced by rods *k k* and pivoted at their angles to the outer sides of the end frames, *B*, by bolts *d*. Said bearers or arms are furnished at their rear ends with handles *f f* and ears *g g*, in which latter are cut slots to accommodate the ratchet-arcs and keys *h h* and *i i*. By this arrangement the reel is adjusted to any desired height by raising or lowering the rear ends of arms *F F*, by means of handles *f f*, which are secured in position on the ratchet-arcs *h h* by the keys *i i*.

The frame of the machine is of only three pieces or hollow sections bolted together by four bolts, as before mentioned. By this arrangement it will be observed that the body of the machine is very economically and durably formed, and made to possess many advantages over the ordinary construction of frame; but as my invention does not relate to the frame-work of the machine I will refrain from further description of it here.

I is the reel-shaft, and *H H*, &c., its beaters, which latter are curved in planes passing through the shaft and so as to approach said shaft near their centers. The ends of said shaft *I* are formed into suitable journals, *l*, which have their bearings in the forward ends of the arms *F*.

It will be noticed that since the bent-up and slotted ends of the cutter-bar *e* lie nearly in the center of the shaft *a*, their position is not much changed by the oscillation of said shaft, though they are somewhat changed. This change does not, however, in the least affect the perfect working of the driving-lever *s* or divider-shank *n*, since the ends of both the lever *s* and shank *n* and bent-up portion of bar *e* are quite thin; and the slots in said bar are made sufficiently wide to allow such change in the relative positions of the several parts without causing any hinderance to their perfect working. Hence the shaft *a* may be oscillated and the cutting apparatus thus elevated and depressed while the same is in full and perfect operation in every other respect.

The divider *G* is so constructed as that when operated in a manner as hereinafter described it will gather the grain beyond the reach of the cutters and outside the line through which the projecting parts of the machine pass into said cutters, said divider having a double curvature and elastic point, and being vibrated rapidly and consequently capable of bringing in every stalk within its reach as it moves inward or toward the cutters, while it slightly presses out and springs past the stalks as it moves outward, bringing in the same stalks at its next inward stroke to the cutters.

Having described fully the construction of the different parts of my improvement, the operation will be readily understood from the following explanation, viz: The machine being carried forward by the required power, the lever *s* is vibrated by any suitable driving mechanism at the proper speed, by which the cutter-bar *e*, carrying the cutters *E E*, is caused to vibrate curvilinearly, whereby a curved cut is made in the standing grain as the machine progresses in like manner as produced by other and well-known machines having a curved platform and cutter. The reel, constructed as before described, being caused to revolve at the same time on its axis, brings the grain against the cutters and throws it when cut on the platform or grain-apron, which should occupy the space marked *A²*, Fig. 1, from whence it may be removed by hand-rakes or an automatic raking attachment. The reel is elevated or lowered, according to circumstances, at the pleasure of the operator by means of the handles *f f*, and is secured in position as before described. The finger-bar *A*, by means of its oscillating shaft *a*, is elevated or depressed at the will of the operator by the handle *m*. As the machine progresses, making a curved cut in the grain from one extremity to the other of the cutting apparatus, in order that the swath may be of sufficient width or that the grain may be cut sufficiently far from the end of the machine that no portion left standing shall be pressed down or injured by the parts of the machine following after the cutters, I give to the divider, which has heretofore been made stationary, a vibratory motion, by which motion and the peculiar form and construction of

the divider I am enabled to gather the grain beyond the reach of the cutters and bring it into said cutters. The vibration to said divider is so little as not to cause it to press down any grain or form a zigzag edge to the cut, but is enough to accomplish, by aid of its quick motion, peculiar form, and elastic point, the desired result of gathering in a very narrow strip of standing grain to the cutters, so that the machine, following after, will perfectly clear the standing grain. From the peculiar form and motions of this vibrating divider, it will be seen (by reference to Fig. 4, where the motions of said divider are indicated by different colored lines) that it springs past the stalks in its backward motion, or when going from the cutters, while it grasps them coming forward, or toward the cutters; and it will be observed that there is little motion to the rear end or butt of the divider, the point *o* acting for the most part to gather in the grain, which, as gathered within the grasp of said point, passes down the in-

clined edge of the divider from *o* to *o* (see Fig. 4) to the cutters as the machine passes forward.

Having fully described the construction and explained the operation of my improvement, what I claim as new, and desire to secure by Letters Patent, is—

1. The vibrating divider *G*, in combination with the cutting apparatus, substantially as described, whereby the grain is gathered into the cutters in order that the parts of the machine following after may perfectly clear the standing grain, as hereinbefore described.
2. The curved or turned-up and slotted ends of the finger-bar *e*, as set forth, in combination with a vibrating lever, *s*, as and for the purpose hereinbefore specified.

I. H. CONKLIN.
